UNITED STATES PATENT OFFICE.

CHARLES W. H. BLOOD, OF BOSTON, MASSACHUSETTS, ASSIGNOR TO S. A. WOODS
MACHINE COMPANY, OF BOSTON, MASSACHUSETTS.

CUTTER-HEAD FOR PLANERS.

1,011,107.

Specification of Letters Patent.

Patented Dec. 5, 1911.

Application filed February 4, 1909. Serial No. 476,183.

To all whom it may concern:

Be it known that I, CHARLES W. H. BLOOD, a citizen of the United States, residing at Boston, in the county of Suffolk and State 5 of Massachusetts, have invented an Improvement in Cutter-Heads for Planers, of which the following description, in connection with the accompanying drawings, is a specification, like letters on the drawings representing like parts.

The main feature of my invention is a cutterhead consisting of a plurality of cutter members each consisting of a frame or carrier and its complement of cutters, said 15 two members being mounted together and separately and removably secured on a spindle to constitute a single cutterhead.

There are many advantages resulting from my invention. In the case of matcher cutterheads, for instance, one frame carries the 20 grooving cutters and the other carries the jointing or straight-edge cutters, so that by tipping the former with relation to the latter the width of the cut made by the grooving member may be increased, in case the 25 projecting grooving cutters cut too tightly. Again, it is always essential that the straight edge of a matched joint shall be preferably true, whereas the tongue and groove need 30 not be so true, and by my invention the grooving member may be removed so as to leave the jointing or straight-edge member undisturbed in its adjustment to be trued by itself. This results in a further important 35 practical advantage, viz., it permits the jointing member to be trued while running. Also, as each member is complete in itself, one member, preferably the one containing the projecting portion or portions of the 40 cutterhead, may be removed as a whole, without disturbing any of its adjustments or the remaining members or any of the adjustments of the remaining members. All 45 the cutters remain set up and are removed from the spindle complete with their carrier, to be put back without readjustment after the remaining or fixed member is trued, ground, or the like. On the other hand, the 50 cutters are individually adjustable. A great variety of cutterhead arrangements may be made at a moment's notice simply by removing one cutter member and putting in place any one of the different members which are kept on hand all sharpened and 55 adjusted, for instant use, ready to be put

on one and the same spindle. The cutter member may also be reversed.

In the preferred form of my invention, the different members are arranged to interlock, one or both sets of cutters overlapping 60 the adjacent carriers. This makes the head strong and also permits the jointing or straight-edge cutter to have its cutting edge extend both above and below or at both sides of the projecting cutters of the grooving member. 65

My invention makes it feasible to have members of different diameters, thereby securing a strong support for those cutters which project forward beyond the other 70 cutters, as in cutting grooved siding, for instance.

My invention includes various details of construction which will be pointed out more at length in connection with the following 75 description, reference being had also to the accompanying drawings, in which I have shown various preferred embodiments of my invention.

In the drawings, Figure 1 is a bottom 80 plan view of one form of the cutterhead; Fig. 2 is a sectional view thereof taken on the line 2-2, Fig. 1; Fig. 3 is a view thereof in side elevation; Fig. 4 is a sectional detail on the line 4-4, Fig. 1; Fig. 5 is a sectional view on the line 5-5 Fig. 1; Fig. 6 is a front elevation of one of the cutters; Figs. 7 and 8 are front elevations of modified cutters; Fig. 9 is a plan view of a slightly different arrangement of cutterhead; Fig. 10 is a projection of the arrangement of the successive cutters of the cutterhead shown in Fig. 9; Figs. 11, 12, and 13 are views in front elevation of various cutters; Fig. 14 is a sectional view on the line 95 14-14 Fig. 9; Figs. 15 and 17 are views in side elevation and plan of a further modification of the invention; and Fig. 16 is a transverse sectional view of a board cut by the cutterhead of Figs. 15 and 17. 100

For convenience of illustration I have herein shown the invention as embodied in a cutterhead consisting of two members, the lower of which is preferably fixed to a cylindrical bearing member or spindle 1 105 adapted to be mounted on the usual cutter shaft by any suitable means as by pins 2.

As shown in Figs. 1, 2, and 3, the upper member consists of a frame or disk carrier 3 provided with a recess 4 for receiving a 110

clamping nut 5 and compensating taper washer 6 for holding the under member of the cutterhead in place. The frame 3 carries the grooving cutters 7 and is separately removable with its grooving cutters in place, this being one of the main features of my invention. The under member consists of a radial flange or carrier 8 constituting a planer head in which are mounted the jointing or straight-edge cutters or knives 9, so that, when the frame 3 and its cutters 7 are removed, the jointing cutters may be trued while the machine is running. I regard this as a very important feature of the invention.

15 It is well known that the cutters of a high speed planer cannot be properly trued except when running at high speed. By my invention the grooving cutters 7 are removed without disturbing their mutual relations, 20 adjustments, etc., thereby leaving the jointing cutters 9 absolutely undisturbed so that they may be trued accurately at high speed, and then thereafter the grooving cutters 7 and their frame 3 are quickly clamped in 25 place again and the cutterhead as a whole is ready for use. The top cutter member is secured by any suitable means as by a nut 10. While the constructional details may be widely varied I have herein shown a specially strong and compact preferred arrangement. Viewing Figs. 3 and 4 it will be seen that the cutters 7 are dovetailed in cross section, to fit a correspondingly shaped groove or way 11 and are held in place by the wedge 30 shape block or end 12 of a bolt 13 and nut 14, said block fitting against the flaring wall 15 of a groove 16 for securing a tight fit and wedging the cutters 7 immovably in place. The frame or carrier 3 is provided 35 with recesses 17, preferably midway between the successive cutters 7, for receiving, preferably snugly, the projecting upper ends of the cutters 9 which occupy a cutting position at each side of the path of the cutters 7, 40 as best shown in Fig. 3. When, as in the preferred construction of the drawings, the recesses 17 are so positioned or formed with relation to the cutters 9 as to receive the latter snugly or at least directly engage the 45 backs of said cutters, great strength is thereby secured, inasmuch as the wide blade 9 has a firm, rigid support or backing throughout substantially its entire extent. Preferably also the cutters and carriers have special 50 holding means, the cutters being herein shown as provided with accurately milled V-shape grooves or notched teeth 18 on one side, to fit correspondingly shaped grooves or teeth 19 in the adjacent wall of the carrier 8, which has a vertical recess 20 for each cutter knife. On its opposite side the cutter is held tightly in position by a clamping back block 21 and bolt 22 whose head 23 has a rocking support or rest in a hollow seat 55 or groove 24 provided therefor in the adja-

cent part of the recess 20 to permit the block to aline itself against the front face or side of the cutter. To keep the block 21 from getting lost whenever the cutters are removed from the frame I provide each block 70 with an ear 25 fitting a slot or groove 26 in which it is held by a pin and slot 27, 28. The corresponding grooves and teeth of all the recesses and all the cutters are similarly placed, so that the cutters are thereby interchangeable. This also brings all the cutting edges into one and the same cutting plane or rotary path. The grooves and teeth 18 hold the cutters positively against slip in the direction of their length. By grooving the 80 cutters longitudinally as indicated at 29, Fig. 7, transverse slipping would be impossible, and by grooving in both directions as at 30, Fig. 8, no slipping in either direction can take place. The clamping blocks are 85 on the forward side of the blades so that the working strain of the blades does not come against the blocks but is brought directly against the solid backing of the head itself.

A further important feature of the cutterhead, in its preferred embodiment, resides in making the frame or carrier 3 capable of a tilting adjustment. For example, in case the grooving cutters 7 cut too tightly, i. e. do not cut the groove in a board or timber of sufficient width to receive properly the tongue on the opposite board or plank, I simply tilt the upper frame 3 on the lower frame 8 by any suitable means, thereby regulating the width of the grooving cut made 10 by the cutters 7. Preferably a set screw 31 is provided for this purpose, threaded through the frame 3 to engage the lower frame member 8, said screw being shown as having dwells or grooves 32 to be engaged 105 by a spring propelled pin 33 to aid the operator in determining the proper adjustment and to hold the set screw in its adjustment. Two feet or raised portions 34 upon the inner edge of the frame or carrier 3 constitute rocking points and unite with the screw 31 in giving the frame or carrier 3 a three-point support upon the lower member 8. This affords accuracy of tilting movement and insures a firm support upon the 110 three points within the tipping range of the head. To facilitate the tilting of the grooving member the frame 3 has a loose fit at 35 and a narrow shoulder 36 to engage a ring or shoulder 37 secured to the spindle at the 115 lower edge of said frame 3, and a compensating or taper washer 38 fits into a correspondingly tapered recess 39 in the underside of the nut 10. In Figs. 9, 14, I have shown the upper member in the form of a 120 comparatively thin plate or frame 40, of substantially the same construction as the lower member, adjusted by a set screw 41 the same as before and held in place by a taper washer 38 and correspondingly hol- 125 130

lowed set nut 10. The construction shown in Fig. 9 enables me to present more clearly the V-shape groove-holding feature of my invention, which is further illustrated in Figs. 5-8 and 10-13, where it will be seen that certain of the groove cutters are provided with transverse holding grooves or teeth slightly diagonal to the length of the cutters in one direction, as indicated at 41, Fig. 11, and others at a different inclination as indicated at 42, Fig. 12, the arrangement of the various cutters in the cutterhead being shown in Fig. 10, where it will be seen that the successive groove cutters are tipped 15 in opposite directions, thereby giving a high cutting corner on one side to half of the groove cutters, and a high cutting corner on the opposite side to the other half of the groove cutters, while the intermediate wide 20 cutters have their grooves or teeth at right angles to the length of the cutters, *i. e.* straight or parallel to the cutting edge as indicated at 43. A further advantage of the holding groove construction is that it facilitates 25 the adjustment and holding of the blades in place. The transverse grooves or teeth 41-43 hold the blade true for its longitudinal adjustment without much aid from the back block 21, so that the operator 30 can readily adjust the blade transversely without losing the longitudinal adjustment. Having adjusted the blade the block is tightened against the blade enough merely to prevent its shifting transversely, inasmuch 35 as the holding teeth or grooves keep the blade true lengthwise. In other words, this groove-and-tooth construction relieves the clamping block of much of its duty as the transverse holding teeth or grooves prevent 40 the cutter from driving back, in use, and hence the holding block 21 need not be set nearly as tightly as would otherwise be required.

A further advantage of my invention is 45 illustrated in Figs. 15-17. The cutter blade frames or carriers may be of any relative shape and extent, and in these figures I have shown an upper member 44 considerably beyond the lower member, so as to make the 50 cut illustrated in the board 45, Fig. 16. Instead of having the upper portion of the blade or part for making the upper cut 46 project from the head a much greater distance than the blade or part which cuts the 55 lower portion 47, by my construction the cutters for both the cuts 46 and 47 can be similarly supported close to their cutting edges, thereby preventing all unevenness due to vibration or springing of the cutter, 60 etc., and relieving the cutter of much strain. By removing the grooving member the cutterhead is adapted to ordinary straight planing. By reversing the member, *i. e.* turning it bottom-side up, the same cutterhead 65 is adapted to run on the opposite spin-

dle so as to run in the opposite direction and operate on the opposite edge of the board or timber.

In use, my invention enables the operator to true the jointing cutters 9 by themselves 70 in their frame or carrier 8, and when running, the grooving cutters 7 being given such attention separately as may be deemed advisable. Thus the jointing knives or cutters are readily brought to an absolutely 75 correct, true and uniform cutting surface simply by removing the grooving member and rotating the jointing member by itself on the cutterhead shaft or on a separate truing spindle. This simplifies the truing 80 of the jointing knives or cutters and greatly facilitates the work, inasmuch as it is not usually necessary to devote much attention to the grooving knives, which need not be so true as the jointing knives. Having trued 85 the jointing member, the cutter head is completed by selecting a grooving member or other co-operating cutting member according to the pattern to be cut, and quickly clamping it in place, thereby at once completing 90 the cutterhead without the necessity of laborious adjustment of the individual knives or cutters. When the work has been finished for that particular pattern, no vexatious delay is required for getting the cutterhead into shape for planing the next pattern, as all that is necessary is simply to take off the entire top member and substitute another one complete, it being understood 95 that as many of these removable members are kept in readiness as the necessities and scope of the work require. All the cutters remain set up in their frames or carriers, and the entire member is removed or put back without requiring any adjustment 100 of the cutters. Whenever the individual cutters get dull a duplicate cutting member is substituted, so that the planing machine is thereby kept in practically continuous 105 service.

As already intimated, my invention is not limited to the constructional details explained, as I believe it is broadly new in the particulars hereinafter specified in the claims, and accordingly I wish it understood 110 that the range of equivalents is intended to be commensurate with the terms of said claims. By the term "grooving cutters" I include any and all shapes of projecting cutters capable of cutting away the stock angularly with relation to the jointing cut or plane of the main surface cut, and by the term "jointing cutter" I include all straight-edge or main-surface cutters (in matcher heads cutting the joint edge of the boards, 115 and in horizontal cutterheads cutting the general plane surface of the boards).

Having described my invention, what I claim as new and desire to secure by Letters Patent of the United States is,

1. A rotary cutterhead for grooving machines, comprising a cylindrical bearing member adapted to be mounted on the cutter shaft, a radial flange removably mounted thereon constituting a planer head, a disk loosely sleeved on said cylindrical bearing member, said disk and said flange being each provided with a set of cutters, certain of said cutters interlocking both with said 10 disk and with said flange, securing means for holding said flange on said cylindrical bearing member independently of said disk, and means for removably securing said disk, whereby to effect withdrawal of 15 the disk and the cutters carried by said disk from the planer head and cutters carried by the planer head to permit grinding of the latter at full speed.

2. A rotary cutterhead for grooving machines, comprising a cylindrical bearing member adapted to be mounted on the cutter shaft, a radial flange removably mounted thereon constituting a planer head, a disk loosely sleeved on said cylindrical bearing head, said disk and said flange constituting cutter carriers and being each provided with a set of cutters, certain of said cutters interlocking with both of said carriers, securing means, mounted in one of 30 said carriers and wholly independent and disconnected from the second carrier, for securing said interlocking cutters fast in their carrier and independent of the second carrier, said second carrier having recesses 35 with walls fitting directly against the backs of the projecting portions of the interlocking cutters throughout substantially the entire width of the projecting portions of said interlocking cutters beyond their own carrier, securing means mounted in said second 40 carrier for securing therein the other set of cutters, which are carried by said second carrier, independently of the first carrier, securing means for holding said flange on 45 said bearing member independently of said disk, and means for removably securing said disk, whereby to effect withdrawal of the disk and the cutters carried by said disk from the planer head and cutters carried by 50 the planer head to permit grinding of the latter at full speed.

3. In a cutterhead for planing machines, a carrier frame provided with means for supporting a cutter against shifting including notched holding teeth, combined with a cutter having teeth at one side fitting said holding teeth, and a self-aligning clamping block pivotally mounted and having one face bearing flat against the side of the cutter opposite the teeth for pressing said holding teeth and cutter teeth interlocked together.

4. In a cutterhead for planing machines, a carrier frame provided with means for supporting a cutter against shifting includ-

ing notched holding teeth in position to support the back of a cutter, combined with a cutter having teeth on its back side fitting said holding teeth whereby the working strain tends to force said teeth into tightly 70 interlocked engagement, and a pivotally mounted clamping block bearing at its front face flat against the side of the cutter which is opposite the teeth thereof for pressing said holding teeth and cutter teeth interlocked together.

5. In a cutterhead for planing machines, a carrier frame provided with a cutter-holding recess, a cutter therefor, a clamping block pivotally connected to the frame to 80 permit its self alinement flat against the side of the cutter from an originally tilted position with relation thereto, and means separate from the pivotal connection of the block for tightening the block against the 85 cutter.

6. In a cutterhead for planing machines, a carrier frame having a cutter-holding recess, and a clamping block permanently held by a pivot pin against removal from 90 the recess in any direction and held loosely in the recess in position to clamp a cutter against the opposite wall of the recess.

7. A cutterhead for planing machines, comprising a cylindrical bearing member 95 adapted to be mounted on the cutter shaft, said bearing member at its lower end terminating in a radial flange, a radial flange constituting a planer head removably mounted on said cylindrical bearing member against 100 said terminal flange, and provided with projecting planing cutters, and means carried by said planer head flange for locking the cutters immovable therein, and a holding and supporting pin projecting perpendicularly from said terminal flange parallel to said cylindrical bearing member into a hole provided therefor in said planer head for holding and supporting the latter in fixed relation to the bearing member, whereby to permit said cutterhead to be reversed 105 to be run in the opposite direction and operate on the opposite edge of a piece of work.

8. In a cutterhead for planing machines, 110 a carrier frame having a cutter-holding recess extending inwardly from its edge, said frame having transverse notched holding teeth at the back side of said recess, combined with a cutter having transverse teeth 115 on its back side fitting said holding teeth for resisting longitudinal movement of the cutter with relation to the frame, the opposite side of said cutter being smooth, a self-aligning clamping block arranged to engage 120 flat against said smooth side of the cutter, and a tightening bolt threaded in said block at one end and having its headed end in rocking engagement with the opposite wall 125 of said recess, said block being entirely free 130

- to swing on the head of the bolt as a pivot when required for self-alining purposes against said smooth side of the cutter.
9. In a cutterhead for planing machines, 5 a carrier frame provided with a cutter-holding recess, a cutter supported against one wall of said recess, and a clamping block and adjusting bolt threaded in said block mounted between the cutter and the opposite wall of said recess, the head of the bolt occupying a rest formed therefor in the adjacent wall of the recess and the block being entirely free to swing on the head of the bolt as a pivot for self-alining purposes.
10. 10. A cutterhead for planing machines, comprising a spindle, a carrier frame and its cutters mounted thereon, and means for clamping said frame in place, including a taper washer and a set nut fitting over said 20 taper washer for permitting a tilting movement of the taper washer and carrier frame with relation to the spindle.
11. A cutterhead for planing machines, comprising a spindle and two carrier frames 25 and their cutters, one frame having a cen-
- tral recess, clamping means mounted on said spindle in said recess for clamping the other carrier frame in position, and means for independently clamping the recessed frame in operative position with relation to the other frame.
12. A cutterhead for planing machines, comprising two carrier frames, separate cutters for each frame, adjusting means for tilting one frame with relation to the other, 35 and bearing feet spaced from each other and from said adjusting means at substantially equal distances extending between said two frames and constituting together with said adjusting means an equidistant three-point 40 support to facilitate the accurate tilting movements.
- In testimony whereof, I have signed my name to this specification, in the presence of two subscribing witnesses.

CHARLES W. H. BLOOD.
